UNITED STATES PATENT OFFICE

114,385

DESIGN FOR TRAILER

Walter O. Wells, Elkhart, Ind.

Application January 3, 1939, Serial No. 82,128

Term of patent 3½ years

To all whom it may concern:

Be it known that I, Walter O. Wells, a citizen of the United States of America, residing at Elkhart, in the county of Elkhart and State of Indiana, have invented a new, original, and ornamental Design for Trailer, of which the following is a specification, reference being had to the accompanying drawings, forming a part thereof.

In the drawings:

Figure 1 is a side perspective view of a trailer embodying my design looking from the right side. The other side is the same except that the door is omitted.

Figure 2 is a view of the interior of the trailer looking towards the rear from about the center.

Figure 3 is a view looking at the interior of the trailer towards the front from about the center.

The characteristic features of my design reside in the interior portions as shown in Figures 2 and 3 of the drawings.

I claim:

The ornamental design for trailer, as shown and described.

WALTER O. WELLS.
